(57) **CLAIM**

I claim, the ornamental design for a combined nail clipper and magnifying glass, as shown and described.

DESCRIPTION

FIG. 1 is a top, front, left perspective view of a combined nail clipper and magnifying glass, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof, showing the magnifying frame including the glass lens;

FIG. 7 is a bottom plan view thereof; and,

FIG. 8 is another top plan view thereof, showing an alternate configuration wherein the magnifying frame does not include the glass lens, for ease of illustration.

1 Claim, 8 Drawing Sheets
